4 Claims. (Cl. 250—207)

The present invention relates to a timer used to control the exposure in photographic printing, and in particular to such a timer employing a multiplier photo tube.

The use of a conventional photo cell to provide a signal proportional to the light transmitted by a negative, and using this signal to charge a timing capacitor to a voltage sufficient to fire a trigger circuit which terminated the photographic exposure, is well known in the art.

Unfortunately the conventional vacuum photo cell has a very low signal output and consequently the leakage currents inevitably present, together with grid emission of the trigger valve, prevent good linearity between the light transmission of the photographic negative and the timing characteristics of systems where the conventional vacuum photo cell is employed.

The use of a multiplier photo cell, while overcoming this disadvantage, introduces several problems.

The polarity of the signal output from a multiplier photo cell is such that either it must be inverted, as by a buffer tube, before being applied to charging a timing capacitor which is arranged to fire a thyratron tube, or it must have its high voltage supply very well isolated from and "floating" with respect to the trigger circuit power supply. The use of two separate power supplies without a common connection makes it difficult if not impossible to properly suppress transients, a lack of stability in the operation which produces erratic exposures.

An object of the present invention is to provide a photographic timer employing a multiplier photo cell and having a simplified circuitry with fewer components than has been required heretofore. This results in a lower first cost and greater reliability.

Another object of the present invention is to provide a bias voltage source for the trigger circuit from the regulated high voltage supply of the photo cell thus securing a reference voltage of great reliability and freedom from voltage fluctuation which is a cause of erratic operation in photographic timers.

A further object of the present invention is to provide a system having a common point of connection between the high voltage supply of the photo cell and the main power supply of the trigger circuit.

Another object of the present invention is to provide a system in which the polarity of the photo cell signal being used to charge the timing capacitor is of the correct polarity to fire the trigger circuit without the intervention of inverter tubes or the like.

A further object of the present invention is to eliminate the need of a voltage divider in the trigger circuit power supply thereby reducing the amount of power required while at the same time eliminating the heat generated thereby.

Another object of this invention is to provide a means for biasing the trigger valve while permitting the cathode of this valve to be connected directly to the negative terminal of the trigger circuit power supply, which resistor acts to restrict the current through the thyratron and the associated relay making it necessary to utilize a sensitive relay for this purpose.

These objects and other advantages of this invention will be best understood from the following description when read in conjunction with the accompanying drawing.

The drawing is a schematic diagram of a photographic timer embodying the present invention. While in general this invention is specifically concerned with a combined

2

photo cell and trigger circuit, sufficient associated apparatus has been shown to form a complete and functioning timer.

The photo cell 11 is of the photo multiplier type, having a cathode 12, dynodes 13 through 21 and an anode 22, all enclosed in an evacuated glass envelope 23. A regulated source of high voltage, schematically indicated as a battery 70, having a resistor 80 in series therewith and having a negative terminal 82 and a positive terminal 83. Between these terminals block 81 indicates schematically a voltage regulating device. A number of suitable devices incorporating glow discharge tubes or solid state devices are well known. Further it should be understood that both the high voltage power supply just described and the main power supply for the trigger circuit may readily be derived by transforming and rectifying commercial A.C. power and in this case the regulation of the high voltage supply may be provided by a voltage regulating transformer or by electronic voltage regulators.

The negative terminal 82 is connected to the cathode 12 and the positive terminal 83 connected to the anode 22; between these two elements is connected a resistance string comprised of resistors 24 through 34 and serving to form a voltage divider so arranged as to provide a D.C. potential starting from the cathode 12 progressively increasing to the anode 22. Thus, a resistor 24 is connected between the cathode 12 and the dynode 13. Another resistor 25 is connected between the dynode 13 and the dynode 14. Resistors 26, 27, 28, 29, 30, and 31 are likewise connected individually between the individual dynode stages 14 through 20. However, resistor 32 is not directly connected between dynode 20 and dynode 21, instead one end of the resistor 32 is connected to plate 41 of a capacitor 35 and the other plate of this capacitor is connected to the dynode 21. Plate 41 is also connected to one end of the resistor 33 and through 34 to the anode 22 and to the positive terminal of the power supply. The power supply 70 would normally be of about 1250 volts when the photo cell 11 is a tube similar in type to the RCA 931A. The plates 41 and 40 of capacitor 35, which acts as the timing capacitor, are normally maintained in a shorted condition by a conductor 36 being connected to plate 41 and a conductor 37 being connected to plate 40, conductors 36 and 37 being shorted by the fixed contact 57 and movable contact 56 of the relay 53. When in this condition each of the dynode stages has a voltage higher than the preceding dynode stage so that the photo cell functions in a normal manner when exposed to light. More specifically, as light strikes the cathode 12 it causes a few electrons to be emitted, and these electrons are drawn over by the relatively higher potential to the first dynode stage 13. The impact of these electrons on the dynode ejects, through secondary emission, a larger number of electrons which are drawn over to dynode 14 which is progressively higher in potential and that this action is so continued until all the electrons produced by the cumulative secondary emission of the various dynodes are drawn over to the anode 22. In the course of this action a number of electrons are drawn from the dynode 20 to the dynode 21 and due to the multiplying action inherent in the tube, for each of these electrons, a much larger number of electrons are ejected from the dynode 21 and drawn over to the anode 22.

A trigger circuit comprising a thyratron tube 45 which has a heater serving as a cathode 46, a grid 47, and an anode 48. The cathode 46 and grid 47 constitute the voltage sensitive input to the trigger circuit, and as is well known, when the potential of the grid is substantially negative with respect to the cathode no current will flow through the tube when power is applied between the anode 48 and the cathode 46. This condition is created by biasing the thyratron 45 in the following way. The heater-

cathode 46, energized by battery 49, is connected to the junction of resistors 33 and 34 by means of conductor 39. The grid of this tube is connected to the plate 40 of condenser 35 by means of conductor 37 and conductor 38. Conductor 37 connects this same plate to the movable contact 56 of relay 53 and the plate 41 of condenser 35 is connected by means of conductor 36 to the fixed contact point 57 of relay 53. Arm 56 and contact 57 are normally closed, thus maintaining condenser 35 in a shorted condition so that there is no potential difference between the plates 40 and 41. The voltage drop of resistor 33 as part of the voltage divider across the power source 70, serves to bias the thyratron 45.

The plate 48 of the thyratron tube 45 is connected by means of conductor 60 to one side of a coil 50 of the relay 49. The other side of the coil 50 is connected to a bus 65, connected to this bus 65 is one terminal of an electro-mechanical shutter 58. The other terminal 67 is connected to a negative terminal of a main power supply shown in a detached relationship so that the triangular symbol G represents the negative terminal of this power pack.

Also connected to the bus 65 is one terminal 61 of a push button 63 and the other terminal of this push button 62 is connected to the positive side of the power pack as denoted by the triangular symbol F. Also connected to the terminal 65 is one side of a coil 71 of a relay 53, the other terminal of said coil being connected to the terminal G of the main power supply. Further the bus 65 extends to make a connection with the relay 53, having movable contact 55 and a normally open contact point 54. A conductor 72 connects point 54 with point 52 of relay 49, the arm 51 of this relay is connected to the positive terminal F of the main power supply.

Having now described the arrangement and connections of the particular embodiment of this invention which is shown in FIGURE 1, the operation of this timer will now be described.

It is understood that a sample of the printing light is directed toward the cathode 12. There are a number of well known methods to do this; for example, a light reflected from the surface of the sensitized material, or beam splitter interposed between the negative and the printing material, or light transmitted through the sensitized material are all practical ways of providing a sample of the printing light.

To start the exposure, the push button 63 is momentarily depressed connecting the positive main power through contact points 62 and 61 to the bus 65. The power thus energizes the electro-mechanical shutter 58 and the shutter opens, starting the exposure. At the same time the coil 71 of relay 53 is energized, the circuit being completed by the other terminal of the coil which is connected to the negative terminal of the main power supply. As soon as the relay 53 is energized, arm 56 is drawn away from the contact point 57 which is normally closed and thus this particular circuit is opened at the same time the contact arm 55 is drawn upward and closes the contact with the point 54 which receives positive power from the conductor 72 connected to point 52 of relay 49, the arm of which 51, is connected to the positive terminal of the main power supply. Thus, contacts 55 and 54 serve as a lock-in, maintaining the relay 53 and the shutter 58 in an energized condition. The coil 50 has one side connected to the bus 65 and the other side of this coil is connected by conductor 60 to the plate 48 of the thyratron 45. Since this thyratron is arranged so that the cathode is at a higher potential than the grid, this tube is blocked and remains in a nonconducting state; therefore, the relay 49 remains de-energized during the exposure period.

It will be remembered that the condenser 35 has been maintained in a shorted condition so that both plates are at a common potential prior to the instant of the start of the exposure. With the opening of the shorting contacts 56 and 57 of relay 53 the short is removed across this con-

denser and it is now capable of changing potential by action of changing its state of charge. The plate 41 being connected to the voltage divider associated with the high voltage power supply is maintained at a reference voltage dependent only upon the values of the resistors in said voltage divider. The plate 40, however, now begins to change potential for the following reason. As electrons are conveyed from dynode 20 to dynode 21 they cause a larger quantity of electrons to be drawn away from dynode 21 and toward the anode 22. If the quantity of electrons being drawn to anode 22 were identical with the quantity of electrons furnished by the dynode 20 there would of course, be no effect on the capacitor 35. However, since the multiplying action of the secondary emission causes many more electrons to be drawn over and away from the dynode 21 this deficit must be made up by the capacitor 35 supplying electrons to the dynode 21. This emission of electrons from the capacitor plate 40 causes this plate to become charged in a positive direction and since this plate is connected through conductors 37 and 38 to the grid of the thyratron trigger tube, the trigger tube will fire after a passage of time which is predetermined by the light intensity and the amount of bias initially supplied to the trigger tube by the resistor 33. As soon as the firing point of the thyratron 45 is reached the tube goes into conduction and closes the circuit across the relay 49 causes the arm to lift breaking the connection between the main power supply and contact 52.

Power is now cut off from the bus 65. Both relays are now free to open and the shutter 58 is de-energized at the same time so that it closes, terminating the photographic exposure. At the same time the contact points 56 and 57 are reclosed, discharging the timing capacitor 35 and placing it in a condition for acceptance of the next printing cycle. Of course, breaking the power supply to the bus 65 cuts off the power to the thyratron 45, terminating its conduction.

It will be noticed that the two power supplies, the main power pack and the high voltage supply, are connected together through resistor 34.

There are several advantages to this. The cathode of the trigger circuit is connected directly to the negative of the main power supply so that the full voltage of this supply is across the thyratron and relay coil without any series resistor, which is normally required when the bias voltage is supplied from the main power supply. There is no voltage divider in this main power supply and hence no loss of power or heat developed. On the other hand the bias voltage is supplied by the regulated high voltage supply, and since it is a requirement that the power supplies for photo multiplier tubes be closely regulated, it follows that the bias potential for the thyratron is also very closely regulated, being in fact, a small percentage of the total fluctuation for the entire power supply. Since this potential is applied through the grid which does not draw current during the timing period, the power is substantially nil and the normal voltage divider required for the photo multiplier tube serves this additional function without added power requirement, and with no appreciable heat generation.

A very important advantage of the present invention lies in the fact that the two power supplies are tied together at a common point by means of the resistor 34 as has been explained previously. This renders it easy to suppress switching transients which would lead to erratic operation, in a way which is completely impossible when the two power systems are left "floating" with respect to one another. Capacitors may be shunted across resistor 33 and/or resistor 34 for this purpose.

Since it is common practice to integrate various program functions with the automatic timer in a photographic printer, it is understood that the present invention may be applied in various ways in practice. I therefore claim as my invention:

75 1. A photographic exposure timer comprising a trigger

circuit power supply, a voltage sensitive trigger valve, having cathode, grid and plate elements, serving to operate exposure terminating means, a photocell voltage supply, a photocell of the multiplier type having a cathode, anode and a plurality of dynodes, arranged to receive a sample of the exposing light and to produce an electrical signal at one of said dynodes as a function thereof, a tapped voltage divider connected across said photocell voltage supply for supplying biasing potentials to said dynodes, a timing capacitor arranged to receive said electrical signal, one side of said capacitor being connected to the grid of the trigger valve and to said one dynode, the other side of the capacitor being connected to the voltage divider, the cathode of the trigger tube being connected to the voltage divider at a point nearer the positive polarized end of the voltage divider than said capacitor connection.

2. A photographic exposure timer comprising a timing capacitor, a trigger circuit power supply, a voltage sensitive trigger valve, having cathode, grid and plate elements, serving to operate exposure terminating means, a photocell voltage supply, a multiplier photocell, having cathode, anode and dynode elements, a tapped voltage divider connected across said photocell voltage supply with the negative polarized end of said divider connected to the photocell cathode and the positively polarized end connected to the anode, all but one of the photocell dynodes being connected to its own tap along the divider, the remaining dynode being connected to one side of said timing capacitor and to the grid element of the trigger valve, the other side of said timing capacitor being connected to a tap on the voltage divider, the cathode of the trigger valve being connected to a tap on the voltage divider at a point more positive than the tap connected to the timing capacitor, switch-means normally closed connected across said timing capacitor and arranged to open at the start of a timing cycle.

3. A photographic exposure timer comprising a photo-multiplier tube having a cathode, anode and a series of dynodes therebetween, power supply means for said photo-multiplier tube including a voltage divider having a plurality of resistance sections with taps connected to said

dynodes, a timing capacitor having one plate connected to the dynode nearest said anode and its other plate connected to one of said taps, means normally providing a shortcircuit across said capacitor, means for removing said shortcircuit at the moment a photographic exposure interval is to be initiated, and means connected to a point between the said dynode nearest said anode and said other plate of the capacitor for terminating said exposure interval when said other plate reaches a predetermined potential.

- interval is to be initiated, and means connected to a point between the said dynode nearest said anode and said other plate of the capacitor for terminating said exposure interval when said other plate reaches a predetermined potential.

10 4. A photographic exposure timer comprising a photomultiplier tube having a cathode, anode and a series of dynodes therebetween, power supply means for said photomultiplier tube including a voltage divider connected between said cathode and anode having tapped resistive portions thereof connected to said dynodes and a further resistive portion connected between said anode and ground, a thyratron having a cathode, anode and grid, said cathode also being connected to ground, a timing capacitor connected between the dynode nearest said anode and one of said tapped resistive portions, said grid also being connected to said nearest dynode whereby said thyratron is biased by said power supply means for said photomultiplier tube, and means in circuit with said thyratron anode and cathode for terminating a photographic exposure interval when said thyratron becomes conductive.
